UNITED STATES PATENT OFFICE.

GEORGE W. GRUVER, OF BAKERSFIELD, CALIFORNIA.

FIREARM.

1,024,989.

Specification of Letters Patent.

Patented Apr. 30, 1912.

Application filed April 19, 1911. Serial No. 622,064.

To all whom it may concern:

Be it known that I, GEORGE W. GRUVER, a citizen of the United States, residing at Bakersfield, in the county of Kern and State of California, have invented a new and useful Firearm, of which the following is a specification.

This invention relates to an improvement in firearms, the primary object of the invention being the provision of a knock-down magazine or repeating firearm of the hammerless type, in which the barrel and magazine are carried by the forward removable portion of the stock, and the fore-stock and the receiver carried by the butt stock is provided with means, whereby the two may be placed into sliding engagement and locked in operable position by means of the magazine.

20 A further object of the invention, is the provision of a means whereby the spring closure piece of the breech mechanism, can be held in open position by the breech mechanism, so that the spring of the magazine 25 will automatically eject unused shells or cartridges when it is desired to unload the said magazine.

Another object of the invention is the provision of means operated by the breech 30 mechanism when ejecting a used shell or cartridge for delivering the unused shell or cartridge from the magazine and simultaneously locking the next shell or cartridge in the magazine.

35 A still further object of the invention is the provision of a breech mechanism, which comprises a receiver connected to and carried by the stock of the firearm, a frame carrying the hammer, shell or cartridge guide 40 and loading means, and the actuating lever, the breech block, and the barrel and magazine carrying portion, thus making the entire gun or firearm in four pieces, the main carrying frame being removably mounted so 45 that the hammer and other adjacent mechanism can be easily cleaned, renewed and repaired.

With the foregoing and other objects in view which will appear as the description 50 proceeds, the invention resides in the combination and arrangement of parts and in the details of construction hereinafter described and claimed, it being understood that changes in the precise embodiment of the 55 invention herein disclosed can be made with-

in the scope of what is claimed without departing from the spirit of the invention.

In the drawings:—Figure 1 is a vertical longitudinal section of a fire-arm embodying the invention, and having one side of the main casing removed and the barrel and magazine portion in elevation, the breech mechanism being in the position it assumes when the barrel is loaded and the hammer set back and held at "safety." Fig. 2 is a sectional view with the hammer in fired position, the breech block being in section, and the hammer also shown partly in section. Fig. 3 is a bottom plan view of the forward end of the frame or receiver. Fig. 4 is a view similar to Fig. 1, on a larger scale, with the breech mechanism in the position it assumes when having ejected a used shell, and about to feed an unused one to the barrel. Fig. 5 is a section taken on line *w-w*, of Fig. 4. Fig. 6 is a cross section taken on line *x-x*, of Fig. 2. Fig. 7 is a detail section taken on line *y-y*, of Fig. 2. Fig. 8 is a detail view of the breech block and the locking and actuating arm of the breech-operating lever in forward locked position. Figs. 9 and 10 are views illustrating the unloading of the magazine. Fig. 11 is a detail perspective view of the frame or receiver of the breech mechanism. Fig. 12 is a detail perspective view of the breech block. Fig. 13 is a detail perspective view of the breech-operating lever. Fig. 14 is a detail view of the main frame which carries the main portion of the mechanism. Fig. 15 is a detail perspective view of the cartridge lock and elevator. Fig. 16 is a detail perspective view of the hammer. Figs. 17 and 18 are detail views of the safety lock and spring. Fig. 19 is a perspective view of the trigger.

Referring to the drawings, A designates the butt end of the stock, B the barrel, C the fore stock, which carries the barrel B and magazine D, the frame or receiver E, being connected to and carried by the butt end A, and provided with means which contacts with the portion C, to permit the gun to be knock-down. As shown the receiver E is provided at its forward end with the flat bridging portion *e*, and the narrow strip *e'*, the two grooves *e'*, forming guides for the reception of the parallel guide strips *b'*, carried by the portion *b*, of the fore-stock C, of the gun. The magazine D, as shown

is rotatably mounted in the fore-stock C, and is limited against inward movement by means of the shoulder 1, at its milled outer end, the portion 2, being adapted to be rotated to engage the threaded portion 3, of the receiver E, and thus lock the gun assembled. To knock down the gun, it is simply necessary to turn the magazine by gripping its milled outer end until the 10 threaded portion 2 thereof is free of the threads 3, of the receiver E, and the fore-stock C, can then be pulled upwardly and out of engagement with receiver E, thus making two members, one carrying the barrel and magazine, and the other the breech mechanism. The receiver E, as before stated is carried by the butt end A, of the stock, and has removably incased therein from the bottom, the main frame F, having the stock engaging end F'', and provided with the hammer pivoting lug 100, the breech-lever limiting lug F', also being integral therewith.

Secured to the forward upper portion of 25 the casing or frame F, is the pair of supporting plates 4, which are arranged in parallel, and have their rear edges 4'', bent inwardly to form a stop for the unused shell or cartridge before being inserted into 30 the barrel. The spring clips 4^a and 4^b, are also carried by these plates 4, and upon one of the plates upon its outer face is mounted the hinged plate 5, of the spring actuated closure or loading trap 6, this 35 being in line with the inner end of the magazine D. Pivotally mounted upon the pin 9, is the cartridge carrier 8, whose forward end is forked and provided with the shouldered enlargements 8^c, the cartridge 40 stop 7, being pivoted to said carrier 8 at 8', and having its pointed and shouldered end 7' and 7'', normally held downward upon the forward end of the frame F, by means of the spring 8'', so that when the 45 parts 8^c, are in either of the positions as shown in Figs. 2 and 4, the shoulder 7'', will always act as a lock to prevent the next unused shell within the magazine from moving backwardly and clogging the 50 breech mechanism. This cartridge carrier 8, as clearly shown, is provided with two lugs 8^a and 8^b, near its pivotal point, these being disposed in the path of the shouldered portions 11^a and 11^b, of the breech 55 operating lever 11, whose hand grip 10, is formed integral therewith. It will thus be seen that a movement of the hand grip 10 toward the stock will cause the shoulder 11^a to abut to the lug 8^b, and cause the carrier 8, 60 to move from the position, as shown in Fig. 4 to the position as shown in Figs. 1 and 2, the gun now being loaded and ready for firing. A movement of the actuating lever 10 in the opposite direction, will after moving 65 the distance between the shoulder 8^a and

the shoulder 11^b, finally bring these shoulders into engagement, when the carrier 8 will be affected and moved from the positions shown in Figs. 1 and 2, to the position shown in Fig. 4, the used cartridge shell having been ejected and an unused one at this time being upon the forked ends of the carrier 8 and ready for delivery to the barrel.

As shown in Fig. 4, the knobbed end 11', of the breech operating lever 11, is disposed below and in line with the groove or slot formed by the shoulders 12 and 12', in the rear end of the breech block G, and when the actuating lever 10 is moved upwardly toward the stock, the knob end 11' will enter said groove between the shoulders 12 and 12', and carry forward the breech block G, until the guide grooves g', fit over the strips g'', of the receiver E, at which time the firing pin 15 will have its point 15' in line and slight contact with the percussion cap of the cartridge. Simultaneously with this movement, the lug 14 and shoulder 14', engage the notch 14'' and the curved portion e³, of the receiver E, and the breech block is now in place. To prevent the accidental movement of the breech block G when in this position, the spring actuated pin 13, seats within notch 11^a, of the lever 11, and in this position the lever 11, forms a lock for the breech block G.

As the breech block G is moved forward into firing position, Figs. 1 and 2, the spring clips or extractor 16, will engage the rim of a shell or cartridge which is now in the barrel; and when the breech block G, is pulled backwardly, these clips carry with the breech block G, the used shell, the lower ejector 16' giving a snapping action to the lower edge of the rim, and thus throwing the used shell through the top opening in the frame or receiver E. Upon the underside of the breech block G, is a spring actuated cartridge stop 17, pivoted at 18, and having the spring 19, this coacting with the shoulder 8^c, to lock the unused cartridges within the magazine D, and preventing any movement thereof while the gun is loaded or after firing, the movement of the breech block G, to unload the used shell, tilting the outer end of the firing pin so that the end 17', of the stop 17 will move above the unused cartridge in the magazine and permit the spring of the magazine to feed said cartridge below the block and back against the projections 4'', where the forked end of the carrier 8, will finally raise the forward end of the said cartridge, so that when the parts are in the position shown in Fig. 4, the cartridge is pointing for the barrel, and has its butt end in a position to be pushed ahead of the breech block G, when it is moved to the position as shown in Figs. 1 and 2, the cartridge stop 7 during this period having its 125 130

shoulder 7" upwardly and backwardly to coact with the projection 8^a, of the forked end of carrier 8, thus preventing the next cartridge within the magazine from passing 5 under the breech mechanism, the next cartridge abutting the said shoulder 7", and projection 8^a, and being held thereby within the magazine. The depending sides 20 of the breech block G are guided upon the 10 upper edges of the strips or plates 4, the spring clips 4^a and 4^b, assisting in holding the breech block within the plates and above the carrier 8 and stop 7.

Mounted upon a pin 22, between the lug 15 100 and the side of the frame or receiver E, is the hammer 21, which is provided with the spring actuated trigger engaging pawl or pin 21', the firing pin striking shoulder or end 21" and the shoulder 21^a, which is 20 adapted to be engaged by the lever 11, so that when the actuating lever 10 is moved away from the stock during the ejecting of a used shell, the hammer is engaged by the lever 11, and also by the breech block G, 25 and moved against the tension of the spring 23, so that it is finally moved from the position shown in Fig. 2, to that shown in Fig. 1. The spring 23 has two terminals 23' and 23", which engage the receiver E and hammer, respectively. When the hammer is 30 moved from the position of Fig. 2 to that in Fig. 1, the spring actuated pin 21' will snap over and be engaged by the shoulder 24' of the trigger 24, and by reason of the trigger 35 spring 25, the hammer will be locked in "set" position. In order to lock the hammer in this position, or at what is termed "safety", that is so that the trigger 24 cannot be moved to release the hammer 21, the 40 rearward projection or lip 24^a, is engaged by the lower end 26', of the lever 26, which is pivoted in the receiver E, intermediate of its ends, and has its upper end 26", mounted in the groove 27', of the slidably mounted 45 safety clip or thumb-button 27, mounted upon the exterior of the casing E, in ready access to the marksman. The position of the parts when at "safety" is shown in Fig. 1, while in the position as shown in 50 dotted lines in Fig. 1, the pivoted catch 26 is out of engagement with the lip 24^a, and any pull upon the trigger 24 will release the hammer and permit the hammer to assume the position as shown in Fig. 2. The spring 55 27" holds the thumb-button 27 downwardly in place on the receiver E.

As is often the case, it is desirous to remove the unused cartridges from the magazine D, and usually to do this, it is necessary 60 to repeat the actions or operations of loading and unloading of the barrel B, and an accidental discharge of the gun may and often does occur, so in order to make unloading of the magazine easy and safe, the trap 6 65 is pushed inwardly and the actuating lever

10 is moved downwardly about one-half the distance required to eject a shell, at which time the shoulder 17' will be in line with and engage the hinge plate 5. This action inclines the trap 6 inwardly and in line with 70 the inner end of the magazine D, giving free egress to the unused cartridges within the magazine, which by reason of the spring tension exerted thereon, will be pushed against the inclined trap 6, which guides 75 the cartridge through the opening e'', of the receiver E, and out of the gun. Thus the cartridges may be loaded and unloaded through the same means. This part of the invention is clearly illustrated in Figs. 9 80 and 10. Should there be any used or unused shell or cartridge in the barrel, after the last unused cartridge has been automatically ejected from the magazine, the actuating lever may be moved still farther away 85 from the stock, and the shell in the barrel will be ejected in the usual manner.

As shown and described, the fore-stock C carries the barrel B, and the magazine D, the rear end thereof fitting within the end 90 of the receiver E, as clearly shown in Figs. 1, 3, 5, 6, and 10, where the receiver and fore-stock are shown operatively connected.

What is claimed, is:—

1. The combination in a firearm, of a 95 breech mechanism, comprising a receiver carried by the stock, a frame carried by the receiver and stock, a breech block removably and slidably mounted in the receiver, a spring actuated hammer carried in 100 said frame, a trigger, and an actuating lever having one end projecting in the receiver and operably connected to the breech block and in the path to engage the hammer for setting the hammer and operating the 105 breech block for extract.

2. The combination in a firearm, of a 110 breech mechanism, comprising a receiver carried by the stock, a frame mounted in the receiver, a breech block removably and slidably mounted in the receiver and frame, a spring actuated hammer carried by the frame, a spring actuated trigger lock carried by said hammer, a trigger to engage 115 said lock, and an actuating lever pivoted in the frame and operably connected with the breech block for sliding the same into and out of cartridge locking position and for cocking the hammer.

3. The combination in a firearm, of a 120 breech mechanism, comprising a receiver carried by the stock, a frame carried by the receiver and the stock, a breech block removably and slidably mounted in the receiver, a spring actuated hammer carried in 125 the frame, a trigger, and an actuating lever pivoted to the frame intermediate its ends and having its inner end extending into operable relation with the breech block and adapted to engage the hammer below the 130

engagement with the breech block when operating the breech block to extract a shell.

4. The combination in a firearm, of a barrel and a magazine, a butt-stock, a receiver 5 open at its bottom attached thereto, a frame carried by the butt-stock and closing the bottom of the receiver, a breech block mounted for reciprocation within the frame, a trigger, a hammer pivoted to the frame, 10 an actuating lever pivoted in the frame and operably connected to the breech block, and means carried by the hammer and in the path of the lever, whereby the hammer is engaged by the lever during the extracting 15 action of the breech block to set the hammer.

5. The combination in a firearm, of a breech mechanism, comprising a receiver and a stock, a frame carried by the receiver and having two upwardly projecting plates, 20 a breech block slidably mounted between said plates and in the receiver, said breech block forming a closure for the receiver when in locked position, cartridge locking and elevating means mounted between said 25 plates below the breech block, a spring actuated hammer carried by the frame, a trigger, and means operably connected with the breech block and cartridge locking and elevating means for operating both simultaneously and in train. 30

6. The combination in a firearm, of a breech mechanism, comprising a receiver carried by the stock, a frame carried by the receiver and having two upwardly projecting plates, a breech block slidably mounted between said plates and in the receiver, said breech block forming a closure for the receiver when in locked position, a spring actuated cartridge locking arm depending 35 from the underside of the block within the plates, cartridge locking and elevating means mounted between said plates below the breech block, a spring actuated hammer carried by the frame, a trigger, and means 40 operably connected with the breech block and cartridge locking and elevating means for operating both simultaneously and in train, the spring actuated arm of the block co-acting with the locking means of the elevator to lock the cartridge in the magazine 45 during the elevation of the previous cartridge to the barrel. 50

7. The combination in a firearm, of a breech mechanism, comprising a receiver 55 and a frame carried by the receiver and having two upwardly projecting plates, a breech block slidably mounted between said plates and in the receiver, said block forming a closure for the receiver when in locked 60 position, cartridge locking and elevating means mounted between said plates below the breech block, a spring actuated hammer carried by the frame, a trigger, and a lever operably connected with the breech block 65 and cartridge locking and elevating means

for operating both simultaneously and in train.

8. The combination in a firearm, of a breech mechanism, comprising a receiver and a stock, a frame carried by the receiver and having two upwardly projecting plates, a breech block slidably mounted between and above said plates and in the receiver, 70 said block forming a closure for the receiver when in locked position, a spring actuated cartridge locking arm depending from the underside of the block within the plates, cartridge locking and elevating means mounted between said plates below the breech block, a spring actuated hammer carried by the frame, a trigger, and a lever 75 operably connected to the breech block and cartridge elevating and locking means for operating both simultaneously in train. 80

9. The combination in a firearm, of a breech mechanism, comprising a receiver and a stock, a frame carried by the receiver and provided with two upwardly extending plates, a breech block slidably mounted between said plates and in the receiver, a lever 90 having its forward end disposed for vertical movement between the plates, an arm carried by said lever, a spring for holding said arm downwardly, co-acting locking means carried by the breech block and lever to lock 95 the cartridges in the magazine, and means for reciprocating the block to operate the lever to elevate a cartridge for insertion by the breech block, the co-acting locking means of the breech block and arm locking 100 the following cartridge in the magazine.

10. In a magazine firearm, the combination of a barrel, a magazine, a reciprocatingly mounted breech block, and a spring actuated trap for the breech opposed to the 105 inner end of the magazine and adapted to be pressed in and engaged by the breech block to retain the trap at an angle across the magazine and permit free egress of the cartridges from the magazine. 110

11. In a magazine firearm, the combination of a spring feed cartridge magazine, a breech mechanism, and a spring trap for the breech mechanism opposed to the end of the magazine, and adapted to be inclined in 115 the path of the cartridges in the magazine and engaged by the breech mechanism to permit free egress of the cartridges from said magazine.

12. In a magazine firearm, a spring feed 120 cartridge magazine, a breech mechanism, a trap for said breech mechanism, and means carried by the breech mechanism to engage the trap to retain the trap diagonally across the path of the cartridges as they are fed 125 from the magazine to permit the automatic emptying of said magazine.

13. In a magazine firearm, a spring feed 130 cartridge magazine, a breech mechanism, a breech block reciprocatingly mounted there-

in, and a trap carried by the breech mechanism adapted to be engaged by the breech block for releasing the cartridges within the magazine to permit the automatic unloading thereof.

5 14. In a magazine firearm, a spring feed cartridge magazine, a breech mechanism having a reciprocatingly mounted breech block therein, a spring arm carried thereby, 10 and a trap for the breech mechanism disposed in the path of the magazine adapted to be engaged by the spring arm and held across the mouth of the magazine to permit of the automatic unloading of the magazine.

15 15. In a magazine firearm, a spring feed cartridge magazine, a breech mechanism provided with an opening to the magazine, a hinged trap therefor, and means for locking said trap across the inner end of the 20 magazine to permit of the automatic emptying of the magazine.

25 16. In a magazine firearm a spring feed cartridge mechanism and breech trap, and means for locking said trap in the rear of and inclinedly across the path of the car-

tridges as the cartridges automatically leave the magazine and are guided away from the breech by the trap thereof.

17. In a magazine firearm, a spring feed cartridge mechanism, a breech block, a 30 breech trap, and a cartridge stop carried by the breech block adapted when not in locked position to engage the trap to release the cartridges and permit automatic ejection thereof from the magazine.

35 18. In a magazine firearm, a spring feed cartridge mechanism, a breech block, a breech trap, and a cartridge stop carried by said breech block, whereby when the trap is depressed to incline across the end of the 40 magazine, the stop will retain said trap to permit the automatic unloading of the magazine.

45 In testimony that I claim the foregoing as my own, I have hereto affixed my signature in the presence of two witnesses.

GEORGE W. GRUVER.
